(57) **CLAIM**

The ornamental design for a base for compressor housing substantially as shown and described.

DESCRIPTION

FIG. 1 is a front, right side, rear and top perspective view of a base for compressor housing comprising a new, original and ornamental design;

FIG. 2 is a left view thereof, the left view being the same as the right view and the rear view;

FIG. 3 is a front view thereof;

FIG. 4 is a top view thereof; and,

FIG. 5 is a bottom view thereof.

The broken lines depict portions of the base for compressor housing that form no part of the claimed design.
